UNITED STATES PATENT OFFICE.

ERNEST N. HUMPHREY, OF NEW BRITAIN, CONNECTICUT, ASSIGNOR TO TRAUT & HINE MFG. CO., OF NEW BRITAIN, CONNECTICUT, A CORPORATION OF CONNECTICUT.

SNAP-HOOK.

1,259,107.

Specification of Letters Patent. Patented Mar. 12, 1918.

Application filed October 9, 1917. Serial No. 195,524.

To all whom it may concern:

Be it known that I, ERNEST N. HUMPHREY, a citizen of the United States of America, residing at New Britain, Hartford county, State of Connecticut, have invented a new and useful Snap-Hook, of which the following is a specification.

My invention relates to improvements in snap hooks, the object being to provide an exceedingly simple, strong and serviceable device comprising a minimum number of parts so designed as to be capable of rapid manufacture at a small cost.

In the accompanying drawings:

Figure 1 is a view showing a front and side elevation of one of the elements, namely, the hook and loop.

Fig 2 is a similar view of another of the elements, namely, the spring.

Fig 3 is a view illustrating a front, side and end elevation of a third element, namely, the clip.

Fig. 4 is a view showing a front and side elevation of certain elements partially assembled.

Fig. 5 is a perspective view relatively enlarged of the finished article.

Fig. 6 is a side view of the finished article partly in section.

The main portion of the device comprises an integral or one-piece hook and loop member, 1 being the hook portion and 2 being the loop or eye portion. This element is preferably formed from a single piece of wire bent to give the desired hook formation and desired loop formation. 3 is an offset at the rear end of the wire which offset is preferably arranged alongside the shank of the hook portion as best seen in Fig. 1. 4 represents a blade spring, the rear end of which is hooked or bent back to form a short extension 4^a. 5 is a spring holding clip having two side flanges 6-6 which are arranged to wrap around the base of the hook shank adjacent to the loop to give a proper finish thereto by covering up the rear end of wire. At the bottom of the channel between the sides 6-6 of the clip is preferably formed a shallow groove 7 shaped to receive the end 4^a of the spring.

Projecting rearwardly from the opposite corners of the base clip 5 are flaps 8-8. These side flaps are designed to be wrapped around the wire of the loop at opposite sides of the hook shank, thereby forming bushings which not only gives a finished

appearance to the article, but which also serve to hold the clip 5 against displacement on the shank of the hook forward of the loop. The two side flaps 8-8 may be provided with shoulders 9-9 which may slightly overlap the opposite sides of the clip so as to hold the sides of the clip when the latter are closed in. 10 is a lug or tongue extending rearwardly from the base of the clip, the function of which is to wrap around the rear end or bend of the spring 4 so as to hold the same in place, as seen in Figs. 5 and 6. In assembling the device, the wire hook and eye member and the clip are first secured together, the sides 6-6 being turned down around the wire of the shank as shown in Fig. 4 and the flaps 8-8 being wrapped around the wire of the loop at opposite sides of said shank. The spring 4 is then applied, the short hooked end 4^a being slid into the pocket formed by the recess 7, the long end of the spring being slipped under the bill of the hook. The lug 10 is then bent around the rear end of the spring so as to hold the same in its operative position. If for any reason it should be desirable to replace the spring, the lug 10 may be bent back and the spring removed and a new one inserted, whereupon the lug would again be bent down. If desired, the sides 6-6 at the rear outer edges may be provided with offset lugs 11-11 which may serve as guides to keep the spring 4 in alignment with the hook bill as shown. By making the hook and loop integral, or in one-piece, great economies are effected, since the same may be made of one continuous length of wire bent by suitable automatic machinery into the desired final form, after which the spring and clip may be quickly attached thereto so as to produce the finished article.

While I have shown my improved snap hook in its preferred form, it should be understood that I do not intend to limit myself to the particular arrangement, design or proportions herein illustrated, since the same may be modified in a variety of ways without departure from the spirit and scope of the invention.

What I claim is:

1. A snap hook comprising a one-piece hook and loop member, the loop extending transversely to the plane of the hook shank, a blade spring bent near its rear end and hooked around that part of the loop in line

- with said shank, a clip extending around said shank forward of said loop, the rear end of said spring projecting into the space between said clip and the hook shank, a lug 5 projecting rearwardly from said clip to hold said spring in place, and means projecting rearwardly from the opposite corners of the base of the clip to wrap around the adjacent parts of the loop for the purpose described.
- 10 2. A snap hook comprising a one-piece hook and loop member, the loop extending transversely to the plane of the hook shank, a blade spring bent near its rear end and hooked around that part of the loop in line 15 with said shank, a clip extending around said shank forward of said loop, the rear end of said spring projecting into the space between said clip and the hook shank, a lug projecting rearwardly from said hook to hold said spring in place, means projecting rearwardly from the opposite corners of the base of the clip to wrap around the adjacent parts of the loop for the purpose described, and spring guarding means carried by said 20 clip to hold said spring in operative alignment with the hook.
- 25 3. A snap hook comprising a one-piece hook and loop member, the loop extending transversely to the plane of the hook shank, a blade spring bent near its rear end and hooked around that part of the loop in line 30 with said shank, a clip extending around said shank forward of said loop, the rear end of said spring projecting into the space between said clip and the hook shank, a lug projecting rearwardly from said clip to hold said spring in place, and means projecting rearwardly from the opposite corners of the base of the clip and extending around the 35 adjacent parts of the loop and overstanding the opposite sides of the clip at the inner end of the latter to reinforce the latter.
- 40 4. A snap hook comprising a hook and loop member formed from a single piece of wire, one end of said wire terminating in a hook bill, the other end of said wire forming the loop and having a short forward offset to lie alongside the base of the hook shank, and forming part thereof, a clip extending around the base of the hook shank to embrace said offset end and tie it to the adjacent part of said shank, a blade spring, one end of the same being held in place by said clip, the other end terminating under the hook bill, with means extending rearwardly from the clip for holding said clip in place against dislodgment.
- 45 5. A snap hook comprising a hook and loop member formed from a single piece of wire, one end of said wire terminating in a hook bill, the other end of said wire forming the loop and having a short forward offset to lie alongside the base of the hook shank and into the space between the clip and the shank, and a rearwardly extending lug carried by said clip operating to hold the spring in operative position, and means for supporting the long end of the spring on opposite sides close to the shank to hold the same in proper alignment with said hook bill.

shank and forming part thereof, a clip extending around the base of the hook shank 65 to embrace said offset end and tie it to the adjacent part of said shank, a blade spring, one end of the same being held in place by said clip, the other end terminating under the hook bill, with means for holding said clip in place against dislodgment on said shank, said means comprising wings extending rearwardly from the rear end of the clip and extending around those parts of the loop on opposite sides of the shank of the 75 hook.

6. A snap hook comprising a hook and loop member formed from a single piece of wire, one end of said wire terminating in a hook bill, the other end of said wire forming the 80 loop and having a short forward offset to lie alongside the base of the hook shank and forming part thereof, a clip extending around the base of the hook shank to embrace said offset end and tie it in operative 85 position, a blade spring, one end of the same being held in place by said clip, the other end terminating under the hook bill, with means for holding said clip in place against dislodgment on said shank, said means 90 comprising wings extending rearwardly from the rear end of the clip and extending around those parts of the loop on opposite sides of the shank of the hook, said clip also including a lug between said wings for 95 holding said spring from disengagement.

7. A snap hook comprising a one-piece hook and loop member formed from a single length of wire one end being bent to form a hook bill at one end and a transversely arranged loop at the other end, the shank of the hook intersecting said loop intermediate its ends, that end of the wire forming the loop portion having a short forward offset arranged alongside the base of the hook 100 shank, a clip member including two side flanges bent to embrace the base of said hook shank and offset portion, the rear ends of said flanges being located forward of and against said loop, lugs extending rearwardly 105 from said clip and arranged to be bent around that part of the loop adjacent to said shank to hold the clip against dislodgment, a blade spring bent intermediate its length to form a long end and a short end, 110 the long end resting under the hook bill, the short end projecting around that part of the loop at the rear end of the hook shank and into the space between the clip and the shank, and a rearwardly extending lug carried by said clip operating to hold the spring 115 in operative position, and means for supporting the long end of the spring on opposite sides close to the shank to hold the same 120 in proper alignment with said hook bill.

125 ERNEST N. HUMPHREY.
